LIQUID FUEL BURNER

James L. Breese, Santa Fe, N. Mex., assignor to
Oil Devices, Santa Fe, N. Mex., a limited partnership of Illinois

Application June 16, 1941, Serial No. 398,294

10 Claims. (Cl. 158—91)

My invention relates to an improvement in hydrocarbon burners and has for one purpose the provision of a burner for burning liquid hydrocarbon fuels which shall be simple, economical and efficient in operation.

Another purpose is the provision of improved means for supplying a burner through a single passage or inlet member with all of the air necessary to support the primary combustion of the fuel.

Another purpose is the provision of improved means for preventing an excess supply of fuel and for cutting off the fuel supply when an excess supply has been delivered.

Another purpose is the provision of improved means for supplying primary and secondary air for the combustion of liquid fuel hydrocarbons along a single inlet member.

Other purposes will appear from time to time in the course of the specification.

I illustrate my invention more or less diagrammatically in the accompanying drawing wherein:

Fig. 1 is a vertical axial section;

Fig. 2 is a section on the line 2—2 of Fig. 1;

Fig. 3 is a section similar to Fig. 2 through a variant form of the device; and

Fig. 4 is a section on the line 4—4 of Fig. 3.

Like parts are indicated by like symbols throughout the specification and drawing.

Referring to the drawing, 1 generally indicates a combustion chamber, herein shown in the form of a drum, having a bottom or base portion 2 and, if desired, a bottom body 3 of fire brick or the like, or any suitable material.

It will be understood that the burner may be applied to a wide variety of heaters, furnaces and the like. I illustrate it, however, in connection with a water boiler 5 having a central flue passage 6. I employ a single air and fuel inlet member having an outer portion 7, herein shown as vertical, and with an open top 8, or any other suitable means for admitting air. It has a horizontal portion 9, which extends inwardly through the wall of the member 1, and is herein shown as terminating with a downward elbow 10 axially aligned with the flue passage 6.

Pivoted to the member 8 is a bucket arm 11, having at its inner end a bucket 12, aligned below the elbow 10 and adapted to receive any liquid fuel which drops therefrom. The bucket arm 11 is normally held in raised position by any suitable means, for example the spring 13. It has, as its inner pivot member, a stem 14, having a screw threaded portion 15 extending through any suit-

able nut or correspondingly screw threaded member 16 formed in or inserted in the wall of the member 8. The stem 14 is aligned with a liquid fuel inlet 17, which is provided with any suitable valve seat 18, opposed to the valve surface 19 on the stem 14.

It will be understood that any suitable means may be employed, not herein shown, for controlling the rate of flow of liquid fuel along the passage 17. The control may be manual or automatic, but is preferably automatic, and a conventional float chamber, for example, may be employed, which does not of itself form part of the present invention.

15 It will be understood that the liquid fuel flowing along the passage 17 is normally free to pass through the valve passage formed by the opposed members 18 and 19. The spring 13 is effective to hold the bucket lever or arm 11 normally in raised position, and when it is in such raised position the valve is open and free to pass whatever liquid fuel is delivered along the passage 17. However, when oil starts to drip in the bucket and its weight becomes sufficient, it will gravitally move the bucket 12 against the spring 13, to the dotted line position. When it does so move, the threads of the opposed members 15 and 16 are of such pitch that the result is a complete closure of the valve and termination of any further fuel flow until the bucket is again raised. However, the air supply continues, and unless combustion has ceased, the air is effective to maintain combustion. After the oil is burned out, the bucket rises, opening the valve 18, 19 for a resumption of oil flow.

35 In the simplest form of the device, as shown in Figs. 1 and 2, all of the primary air is supplied through the conduits 7, 8 and 10, and combustion is maintained at the inner end of the member 10. 40 I may provide any suitable secondary air supply means. In the form of Figs. 3 and 4, an inlet member 9a is employed, having an intermediate horizontal partition 20. The space below the partition 20 receives air from the air tube 7a, 45 which corresponds to the air tube 7 of Fig. 1.

The above described fuel valve is arranged to communicate with the space in the passage 9a below the partition 20 and operates in conjunction with the bucket, as above described. However, secondary air may be supplied through the air tube 21, which communicates with the space above the partition 20.

50 I may employ any suitable means for discharging this air and any suitable aperturing of the upper wall of the passage 9a. I find it

practical, however, to employ a distributor having the upwardly extending stem 22, the head 23, and the side apertures 24 in said head whereby the supply of secondary or additional air is delivered into the space about or above the passage 9a.

It will be realized that, whereas I have described and illustrated a practical and operative device, nevertheless many changes may be made in the size, shape, number and disposition of parts without departing from the spirit of my invention. I therefore wish my description and drawing to be taken as in a broad sense illustrative or diagrammatic, rather than as limiting me to my precise showing.

For example, the shape and proportion of the primary and secondary air passages may be widely varied, and a simple aperture or plurality of apertures may be employed, or a variety of different shapes of head. It will be understood, also, that, if I wish, I may provide some additional air supply to the combustion chamber 1, but under many circumstances it is preferable to deliver all of the air supply through the passages 1, 1a or 21.

The use and operation of my invention are as follows:

I provide a heating device in which a liquid fuel, such as liquid hydrocarbon, may be burned. I have illustrated my device in connection with a structure suitable for a hot water heater, but it will be understood that I may apply it to space heaters, furnaces, or the like, or any other heating means.

Basically, I employ an inlet passage of substantially greater capacity than is necessary for the mere supply of a liquid fuel to be burned. In the form of Fig. 1 I illustrate an air passage of substantial cross sectional area, which receives air at the open top 8 and delivers the air inwardly along the passage 9. The liquid fuel is admitted along the passage 17, past the valve members 18, 19, and flows inwardly along the passage 9. As a substantial length of the passage 9 is subjected to the heat of combustion within the member 1, the area through which the mixture of primary air and the liquid fuel flows is highly heated. Enough air is admitted to constitute the entire primary supply of air, and the liquid hydrocarbon, in the presence of this primary air, is vaporized and forms, with the primary air, a hydroxylated mixture.

The mixture is supplied at a speed exceeding that of flame propagation, so that the mixture cannot burn back into the passage 9, with a consequent deposit of carbon. It will be understood that I may employ any means for maintaining this relatively high flow of mixture. If in any particular situation natural draft is not sufficient, I may employ a motor-driven fan, or other suitable means not herein shown.

Fuel is supplied at sufficient volume to maintain a fire which will subject the passage member 9 to temperatures sufficient to vaporize the liquid fuel and to superheat the final mixture. When the mixture escapes from the downturned end 10 of the passage 9, it receives sufficient secondary air in the space defined by the drum 1 to produce a final mixture which is burned in the combustion chamber.

I may employ any additional suitable inlet means for supplying this secondary air. I illustrate, for example, in Figs. 3 and 4, a separate air passage which, as a matter of convenience, may be formed unitarily with the passage 75

through which the liquid fuel flows. In Figs. 3 and 4 I illustrate a header which distributes the secondary air to the space about the end of the inlet 10, from which the primary mixture escapes. It is advantageous to so deliver the secondary air as to maintain a zone of combustion directly adjacent the passage 10 so that the liquid fuel is properly vaporized and the primary mixture superheated.

10 I may employ any suitable means for controlling the rate of flow of the fuel inwardly along the passage 17. As float chambers and the like are well known in the art, I am not indicating any particular means in the present drawing.

15 I find it advantageous to provide means for cutting off the fuel supply in the event that an excess supply of fuel, more than can be vaporized, is delivered from the outlet 10. I illustrate, for example, the drip bucket 12 on the arm 11, which is normally held in raised position by the spring 13. If excess liquid fuel is delivered to the bucket 12 in a volume or weight sufficient to depress it, it may then drop to the dotted line position. When it does so drop, it rotates the valve stem 14, and thence, by the action of the thread 15 and the nut 16, moves the valve member 19 to closed position and reduces or cuts off the further supply of fuel.

20 After the fuel in the bucket 12 has been removed or has burned off or has been consumed, then the spring 13 is effective to raise the arm 11 and the bucket 12 to the full line position of Fig. 1, and the supply of liquid fuel is resumed. 25 It would be evident that the fuel flow cannot recommence until the bucket has been raised to the full line position of Fig. 1, and this cannot happen until either the operator has emptied the bucket or the contents of the bucket have burned off.

30 In all of the forms herein, oil flows from the line 17 through the valve orifice into the tube 9, and flows out along the tube, which is pitched somewhat downwardly toward the mouth 10. The oil starts in as a liquid after passing the valve 18, and rolls down the lower surface of the tube 9. Before it reaches the orifice 10 it is vaporized by the heat of combustion.

35 The air passing through the tube 9 is sufficient to completely hydroxylate the mixture, and a dry combustible gas flows downwardly through the orifice 10 at a velocity greater than that of flame propagation. This velocity is sufficient to prevent flame from burning back into the tube.

40 Any suitable secondary air supply means may be employed for supplying secondary air to the space within the drum or housing 1. In Fig. 1 I illustrate for example a clearance or space in which the lever 11 is free to move. It will be understood that in any event secondary air is admitted to the space within the drum 1 and that this secondary air is sufficient and effective to maintain final complete combustion of the mixture which flows from the orifice 10. In Figs. 45 to 2 to 4 I illustrate other specific means for admitting the necessary secondary air for completing combustion.

45 I claim:

50 1. In combination, a closed combustion chamber, a flue extending therefrom, a tubular inlet passage element extending through the wall of the combustion chamber and extending generally horizontally a substantial distance into the chamber, said tubular element being spaced substantially above the bottom of the chamber and hav-

ing a downwardly directed discharge end, means for delivering a controllable volume of liquid hydrocarbon to said tubular element in a volume substantially less than sufficient to fill the tubular element, the extension of the tubular element into the combustion chamber being sufficient to insure substantially complete vaporization of the liquid hydrocarbon prior to its reaching the discharge end of the tubular element, and means for admitting outside air for delivery through said tubular element in sufficient volume to support complete combustion within the chamber, of the mixture delivered from the tubular element, and means for controlling the inflow of liquid fuel to the tubular element, including a fuel receiving pan located in the combustion chamber and vertically aligned with the discharge end of the tubular element, and a valve element for said liquid fuel, and valve actuating means connecting said pan and said valve element and adapted, in response to a predetermined weight of fuel in said pan, to move said valve element toward closed position.

2. In combination, a closed combustion chamber, a flue extending therefrom, a tubular inlet passage element extending through the wall of the combustion chamber and extending generally horizontally a substantial distance into the chamber, said tubular element being spaced substantially above the bottom of the chamber and having a downwardly directed discharge end, means for delivering a controllable volume of liquid hydrocarbon to said tubular element in a volume substantially less than sufficient to fill the tubular element, the extension of the tubular element into the combustion chamber being sufficient to insure substantially complete vaporization of the liquid hydrocarbon prior to its reaching the discharge end of the tubular element, and means for admitting outside air for delivery through said tubular element in sufficient volume to support complete combustion within the chamber, of the mixture delivered from the tubular element, and means for controlling the inflow of liquid fuel to the tubular element, including a valve adapted to control the flow of liquid fuel into said tubular inlet passage and means for closing said valve when an excess supply of fuel has been delivered along the tubular inlet passage.

3. In combination, a closed combustion chamber, a flue extending therefrom, a tubular inlet passage element extending through the wall of the combustion chamber and extending generally horizontally a substantial distance into the chamber, said tubular element being spaced substantially above the bottom of the chamber and terminating in a downwardly directed discharge end adjacent the center of the chamber, means for delivering a controllable volume of liquid hydrocarbon to said tubular element at a point substantially removed from the delivery end of the tubular element in a volume substantially less than sufficient to fill the tubular element, the extension of the tubular element into the combustion chamber being sufficient to insure substantially complete vaporization of the liquid hydrocarbon prior to its reaching the discharge end of the tubular element, means for admitting outside air for delivery through said tubular element in sufficient volume to support complete combustion within the chamber, of the mixture delivered from the tubular element, means for controlling the inflow of liquid fuel to the tubular element, including a fuel receiving pan located in the combustion chamber and vertically aligned with the dis-

charge end of the tubular element, a valve element for said liquid fuel, and valve actuating means connecting said pan and said valve element and adapted, in response to a predetermined weight of fuel in said pan, to move said valve element toward closed position.

4. In combination, a closed combustion chamber, a flue extending therefrom, a liquid fuel inlet passage member adapted to deliver a liquid fuel to said chamber, means for supplying liquid fuel to said passage member and means for controlling the inflow of liquid fuel to the passage member including a valve, and means for closing said valve, including a cup located within the interior of said combustion chamber, and aligned with the discharge end of said passage member and adapted to receive liquid fuel delivered from the passage member, said cup having an open top, the interior of said cup being subjected directly to radiant heat from combustion taking place within the closed combustion chamber, and an actuating connection between said cup and said valve.

5. In combination, a closed combustion chamber, a flue extending therefrom, a liquid fuel inlet passage member adapted to deliver a liquid fuel to said chamber, means for supplying liquid fuel to said passage member and means for controlling the inflow of liquid fuel to the passage member including a valve, and means for closing said valve, including a cup located within the interior of said combustion chamber, and aligned with the discharge end of said passage member and adapted to receive liquid fuel delivered from the passage member, said cup having an open top, the interior of said cup being subjected directly to radiant heat from combustion taking place within the closed combustion chamber, and an actuating connection between said cup and said valve, said passage member having a downwardly directed discharge end portion aligned with said cup.

6. In combination, a closed combustion chamber, a flue extending therefrom, a liquid fuel inlet passage member adapted to deliver a liquid fuel to said chamber, means for supplying liquid fuel to said passage member and means for controlling the inflow of liquid fuel to the passage member including a valve, and means for closing said valve, including a cup located within the interior of said combustion chamber, and aligned with the discharge end of said passage member and adapted to receive liquid fuel delivered from the passage member, said cup having an open top, the interior of said cup being subjected directly to radiant heat from combustion taking place within the closed combustion chamber, and an actuating connection between said cup and said valve, and yielding means adapted normally to urge said valve toward valve opening position.

7. In combination, a closed combustion chamber, a flue extending therefrom, a liquid fuel inlet passage member adapted to deliver a liquid fuel to said chamber, means for supplying liquid fuel to said passage member and means for controlling the inflow of liquid fuel to the passage member including a valve, and means for closing said valve, including a cup located within the interior of said combustion chamber, and aligned with the discharge end of said passage member and adapted to receive liquid fuel delivered from the passage member, said cup having an open top, the interior of said cup being subjected directly to radiant heat from combustion taking place within the closed combustion chamber, and an actuating connection between said cup and

said valve including a valve controlling lever upon one end of which said cup is mounted and yielding means, connected to said valve controlling member, and adapted normally to urge it toward valve opening position.

8. In combination, in a liquid fuel burner, a mixing and combustion chamber element therefor, having air inlet means, means for delivering a liquid fuel to the interior of said chamber member, a liquid fuel receiving cup, located in said interior of said chamber member and in the line of delivery of liquid fuel to the interior of said chamber member, and means for varying the flow of liquid fuel to the interior of said chamber member in response to the weight of the liquid fuel in said cup.

9. In combination, in a liquid fuel burner, a mixing and combustion chamber element therefor, having air inlet means, means for delivering a liquid fuel to the interior of said chamber member, a liquid fuel receiving cup, located in said interior of said chamber member and in the line

of delivery of liquid fuel to the interior of said chamber member, and means for varying the flow of liquid fuel to the interior of said chamber member in response to the weight of the liquid fuel in said cup, including valve means responsive to downward movement of said cup.

10. In combination, in a liquid fuel burner, a mixing and combustion chamber element therefor, having air inlet means, means for delivering a liquid fuel to the interior of said chamber member, a liquid fuel receiving cup, located in said interior of said chamber member and in the line of delivery of liquid fuel to the interior of said chamber member, and means for varying the flow of liquid fuel to the interior of said chamber member in response to the weight of the liquid fuel in said cup, including valve means responsive to downward movement of said cup.

11. In combination, in a liquid fuel burner, a mixing and combustion chamber element therefor, having air inlet means, means for delivering a liquid fuel to the interior of said chamber member, a liquid fuel receiving cup, located in said interior of said chamber member and in the line of delivery of liquid fuel to the interior of said chamber member, and means for varying the flow of liquid fuel to the interior of said chamber member in response to the weight of the liquid fuel in said cup, including valve means responsive to downward movement of said cup, and yielding means tending normally to hold said cup at a predetermined upper position, with said valve means in maximum flow position.

JAMES L. BREESE.
